CLAIM

The ornamental design for a pressure washer pump, as shown and described.

DESCRIPTION

FIG. 1 is a bottom-front perspective view of a pressure washer pump having a first mounting configuration; FIG. 2 is a top-front perspective view thereof; FIG. 3 is right side-front perspective view thereof; FIG. 4 is a front elevation view thereof; FIG. 5 is a rear elevation view thereof; FIG. 6 is a bottom plan view thereof; FIG. 7 is a top plan view thereof; FIG. 8 is a right side elevation view thereof; FIG. 9 is a left side elevation view thereof;

FIG. 10 is bottom-front perspective view of the pressure washer pump having a second mounting configuration; FIG. 11 is a right side-bottom perspective view of the pressure washer pump having the second mounting configuration;

FIG. 12 is bottom-front perspective view of the pressure washer pump having a third mounting configuration; and, FIG. 13 is a right side-bottom perspective view of the pressure washer pump having the third mounting configuration.

The broken lines are included for the purpose of illustrating portions of the pressure washer pump that form no part of the claimed design.

1 Claim, 13 Drawing Sheets
